CIRCUIT CONTROLLING APPARATUS

Alf E. Anderson, Milton, Mass.

Application February 15, 1934, Serial No. 711,378

7 Claims. (Cl. 200—17)

This invention relates to circuit controlling apparatus of that character in which a movable contact member is moved step by step in opposite directions to be engaged with stationary contact members or terminal blocks, with which are connected storage battery or like cells, which are designed to be added to or cut out of a circuit whose strength of current is to be increased or diminished to meet conditions of use.

10 The invention has for its object to provide a simple, efficient and superior apparatus as will be described.

The particular features of the invention will be pointed out in the claims at the end of this 15 specification.

In the accompanying drawings,

Fig. 1 is a front elevation with parts in section, of one form of circuit controlling apparatus embodying this invention, the section being taken 20 on the line 1—1, Fig. 2;

Fig. 2, a section on the line 2—2, Fig. 1;

Fig. 3, a front elevation on a larger scale of the movable brush-carrying member shown in Fig. 1;

25 Fig. 4, a side elevation of Fig. 3 with the brushes and a part of their carrier shown in section, the latter being taken on the line 4—4, Fig. 3;

Fig. 5, a section on the line 5—5, Fig. 3;

30 Fig. 6, an elevation on an enlarged scale of the oscillating disk shown in Fig. 1, which effects oscillation of the brush-carrying member;

Fig. 7, a side elevation and section of the disk and attached parts shown in Fig. 6;

35 Fig. 8, an enlarged detail in section on the line 3—8, Fig. 6; and

Fig. 9, an enlarged detail of the adjustable link shown in Fig. 1 and which will be referred to.

In the present instance, the invention is illustrated in a circuit-controlling apparatus of the type shown and described in U. S. Patent No. 996,960 dated July 4, 1911 and is an improvement thereon as will be described.

40 In the apparatus herein shown, a plurality of individual stationary contact members or terminal blocks 12 are arranged to form part of a circle having the center 13, which also constitutes the center for a curved bus bar 14 of smaller radius than that of the circle in which the individual stationary contact members 12 are located.

45 The bus bar 14 and the stationary contact members 12 have co-operating with them a movable contact member of a novel construction as will be described and which is associated with an oscillating carrier which is loosely mounted on

the pin or shaft 13 constituting the common center for the circularly arranged contact members 12 and the bus bar 14.

The movable contact member is composed of two laminated brushes 16, 17, arranged to have 5 the opposite ends of each brush engaged with the bus bar 14 and with a stationary contact member 12, whereby a maximum and equal contact between the brushes and the bus bar and its stationary contact members may be obtained. 10

Another object of the present invention is to automatically compensate for wear at the ends of the brushes and thereby maintain the maximum contact under conditions of use and equalize the resistance at the surfaces in contact and 15 minimize the heat at the contact surfaces. To this end provision is made whereby the brushes have a floating relation to the oscillating carrier for said brushes, so that they may move in a plane transversely of the path in which they are 20 moved by the oscillating carrier.

In the present instance the brushes 16, 17 are moved in a circular path to establish electrical connection between the bus bar 14 and one of the individual stationary contact members 12, and 25 are also capable of movement in a plane transversely of or radially with relation to said circular path, which enables the opposite ends of the brushes to adjust themselves with relation to the bus bar and stationary contact members independently of the oscillating carrier. This floating connection of the contact brushes 16, 17 with their carrier may and preferably will be obtained by providing a loose mechanical connection between the brushes and their carrier, and such 30 connection may be obtained as will now be described. To this end a bolt or spindle 20, shown best in Figs. 3, 4 and 5, has one of the brushes, as 17 fastened to it to move therewith, while the other brush 16 is loosely mounted on the bolt 20 to enable the brush 16 and the bolt to be moved 35 with relation to each other. The brush 17 is clamped on the bolt 20 between a plate or member 22 and a head 23 on the bolt and is secured in fixed relation to the bolt by screws 24 extending 40 through the head 23 and the brush 17 into the plate 22. The brush 16 is secured in fixed relation to an inner plate 25 and an outer plate 26 by screws 27, and said brush 16 and its clamping plates 25, 26 are mounted as a unit on the bolt 45 20 and are provided with holes 28 of larger diameter than the bolt, so that the brush 16 and its clamping plates may be moved as a unit longitudinally of and transversely with relation to the bolt. The movement of the brush unit length- 50 55

wise of the bolt 20 may be effected by adjusting nuts 30 on the free end of the bolt which co-operate with the outer clamping plate 26 of said unit.

5 This arrangement provides for adjustment of the brushes 16, 17 from one side of the stationary contact members 12 and of the bus bar 14, whichever side is more accessible, without removing the brushes from their oscillating carrier.

10 The transverse movement of the brush unit 16, 25, 26 on the bolt 20 permits both ends of the brush 16 to compensate for any irregular contact at either end of the brush 16, due to uneven wear or other irregularities which may arise, as the brush 16 may automatically adjust itself to compensate for such irregularity and thereby provide for equal and uniform contact at each end of the brush 16 and thus ensure equal distribution of current from the bus bar 14 to the stationary 15 contact member 12 with which the brush 16 is engaged. The brush 17 is also capable of automatically compensating for irregularities by reason of the loose connection between the bolt 20 and the brush 16.

25 The brushes 16, 17 are designed to be moved as a unit from one stationary contact 12 to another, and to this end, they are connected with an oscillatory or reciprocating carrier, which connection is effected as herein shown by a spider or device having a hub 32 located between the brushes 16, 17 in the space 33 between the bus bar 14 and the stationary contact members 12. The hub 32 is loosely mounted upon the bolt 20 so that the bolt may slide through the hub 32 when the brush 17 is adjusted to the bus bar 14 and contact members 12. The hub 32 has attached to it two pairs of arms 34, 35 located on opposite sides of the brushes 16, 17 and said arms are preferably constructed so as to obtain a very slight clearance at the ends of the arms and a materially greater clearance intermediate the said ends as clearly shown in Figs. 3 and 5.

To this end each of the arms 34, 35 is provided at its opposite ends with inwardly extended portions 36 of sufficient area to obtain a substantial bearing against the brush with which it cooperates, while at the same time reducing the area of contact of the arms with the brushes and thereby avoid interference of the arms with the movement of the brushes, when the latter are manually or automatically adjusted to the bus bar 14 and stationary contact members 12.

55 For sake of clearness, the arms 34, 35 may be designated as pusher arms, as they function to push or move bodily the brushes 16, 17 as a unit from one stationary contact 12 to another.

It will be understood that a pair of pusher arms 34, 35 cooperates with each of the brushes 16, 17, as clearly shown in Fig. 5.

60 The bodily movement of the brushes 16, 17 by the pusher arms 34, 35, may be effected by an oscillating device, which in the present instance consists of a lever 40 provided with a hub 41, which is loosely mounted to turn on the shaft or pin 13, (see Fig. 1). The lever 40 is provided at its upper end with forks 42, 43, to which the hub 32 is fastened by screw bolts 45 (see Figs. 3 and 5), or it may be fastened in any other suitable manner.

70 In the present instance, the lever 40 is oscillated by means of pawls 46, 47 (see Fig. 1) pivotally mounted on the lever 40 and cooperating with teeth 48 on the periphery of a disk 49 provided with a hub 50 which is loosely mounted on 75 the center pin or shaft 13 (see Fig. 2). The teeth

48 extend transversely of the disk 49 and have co-operating with them a cam ring 52 carried by the disk 49 and movable on the disk in an annular guideway 54, formed by a reduced portion of the disk at one side thereof and a retaining ring 55 which is secured to the side of the disk 49 by screws 56 (see Figs. 6 and 7).

The cam ring 52 is provided with oppositely inclined portions 58, 59, which constitute cams and co-operate with the toothed disk 49 to permit the pawl 46 or 47 to engage a tooth of the disk 49 in one position of the cam ring 52 with relation to the toothed disk 49, and to prevent such engagement of the pawl 46 or 47 with a tooth in another position of the cam ring 52 with relation to the toothed disk 49. By reference to Fig. 6, it will be observed that the portion of the cam ring 52 between adjacent cams 58, 59 projects above the circumference of the toothed disk 49, so that when the cam ring 52 is rotated on the disk 49 into a position wherein the low part of the cams are in line with a tooth 48 on the disk 49, the pawl co-operating with such tooth can engage the tooth and be moved by rotation of the disk 49 the distance of one tooth, which allows the toothed disk 49 to move the brush-carrying lever 40 in the proper direction to move the brushes 16, 17 from one stationary contact member 12 to the next adjacent contact member 12.

30 It will thus be observed that the toothed disk 49 acts as a driver or mover for the oscillating lever 40, and moves the same and the brushes carried thereby in the proper direction to effect the desired change in the circuit in which the 35 brushes are included.

The toothed disk 49 may be moved by hand or by power. To move it by power the toothed disk 49 is connected with an electric motor 60 (see Fig. 1) having its armature shaft 62 provided with a worm 64, which meshes with and drives a worm gear 66 fast on a shaft 68 and having a crank 70 thereon connected with a crank pin 72 on the disk 49 by a connecting rod 73. The toothed disk 49 is moved in the direction indicated by the arrow 74, Fig. 1, when the connecting rod 73 is moved forward by a half rotation of the worm gear 66 in the direction of the arrow 74, and said disk 49 is moved in the direction opposite to that of the arrow 74 when 50 the connecting rod 73 is moved in the direction opposite to that indicated by the arrow 74 on the second half rotation of the worm gear 66.

The disk 49 may be manually moved by a crank or handle 74 which is removably engaged 55 with the end of the shaft 68 of the worm gear.

The connecting rod 73 is made adjustable so that the teeth of the disk 49 may be adjusted or properly positioned with relation to the cams 58, 59 of the cam ring 52 and enable the contact 60 brushes 16, 17 to be centrally located with relation to the sides of the stationary contact member 12 with which they are engaged when they come to rest.

The adjustable connecting rod 73 is preferably 65 made as shown in Fig. 9 and consists of a member 76 for engaging the stud 72 on the disk 49, a like member 78 for engaging the stud 70 on the worm gear 66, and a threaded rod 80 for engaging threaded sockets in the members 76, 78. 70 The threaded rod 80 is provided with a collar 81 for engagement by a wrench or other suitable tool by which the threaded rod 80 may be turned to lengthen or shorten the connecting rod.

The socketed ends of the members 76, 78 are split lengthwise to be compressed by the screws 82 and thereby secure the threaded rod 80 and the members 76, 78 in fixed relation in their 5 adjusted position.

The teeth 48 on the disk 49 are arranged in two opposing sets (see Fig. 6), which may be designated the right and left sets, and the cam ring 52 is arranged with relation to the disk 49, 10 so that the teeth of the right set are uncovered by the cams 58 to permit the pawl 46 to be engaged with the teeth constituting the right set; and so that the teeth of the left set are covered by the cams 59 cooperating therewith so as to 15 prevent the teeth of the left set being engaged by the pawl 47 (see Fig. 1) at the same time.

The teeth 48 of the right set cooperate with the pawl 46 to turn the lever 40 toward the left viewing Fig. 1, and thereby move the contact 20 brushes toward the left, from one contact member 12 to the next adjacent contact member 12, when it is desired to remove or cut out a cell from the circuit. The teeth 48 of the left set cooperate with the pawl 47 to turn the lever 40 25 toward the right and move the brushes onto the next contact member 12 toward the right when a cell is to be added to the circuit.

The rotation or movement of the cam ring 52 in opposite directions on the toothed disk 49 30 is effected by a cam bar 86 (see Figs. 1 and 6) provided with side flanges 87, which slide in a guideway in a guide 88 affixed to the toothed disk 49. The cam bar 86 is provided on its opposite sides with inclined surfaces 89, 90, which 35 constitute cams and cooperate with rollers 91, 92 carried by the cam ring 52.

The cam bar 86 is reciprocated between the rollers 91, 92 and on its up movement or stroke in the direction of the arrow 93, Fig. 6, the cam 40 89 is engaged with the roller 91 and the cam ring 52 is moved or rotated on the toothed ring 49 in the direction indicated by the arrow 94, so as to lift the pawl 46 and cover the teeth of the right set, and so as to uncover the teeth of the 45 left set and allow the pawl 47 to engage with a tooth of said left set. On the down stroke of the cam bar 86 in the direction opposite to that indicated by the arrow 93, the cam 90, which at such time is above the roller 92, engages the latter and moves or rotates the cam ring 52 in 50 the direction opposite to the arrow 94, so as to lift the pawl 47, cover the teeth of the left set and uncover the teeth of the right set.

Provision is made for locking the cam bar 86 55 against movement and thereby prevent accidental movement of the cam ring as for instance by vibration, which would render the apparatus inoperative or at least non-reliable under conditions of use in which vibration may arise. To 60 this end, means are provided for automatically locking the cam bar 86 in its elevated position and preferably also in its lowered position.

A preferred construction of locking means is 65 herein shown (see Fig. 6), which consists of a pin or bolt 96 slideable in an opening 97 in one of the side bars of the guide 88 and actuated by a spring 98 to enter a socket or notch 99 in a side flange 87 of the cam bar when the latter is in its elevated position.

The inner end of the locking pin or bolt 96 is 70 substantially V-shaped, as is also the socket or notch 99, so that when the bolt is entered into the socket 99, the cam bar will be locked in its elevated position against release by vibration but 75 will be unlocked by positive movement of the

cam bar downward, which movement may be effected as herein shown by manual operation or automatically as will be described.

The cam bar may also be locked in its lowered position, shown in Fig. 6, by providing the flange 5 87 of said bar with a second notch 190 with which the bolt or pin 96 co-operates.

The cam bar 86 is moved into its extreme upward position by an electromagnet or solenoid 100 and is moved into its lowered position by a 10 solenoid 101 (see Fig. 2), which solenoids are opposed to each other and have a common armature or core 102 provided with an adjustable connecting rod composed of the members 103, 104. The member 103 has a ball and socket connection 15 with the armature 102 and has its upper end screw-threaded to enter a threaded socket in the lower end of the member 104. The upper end of the member 104 is pivotally connected with the cam bar 86. When the solenoid 101 is energized, the armature 102 is attracted and moved downward assisted by gravity, whereas when the solenoid 100 is energized the armature 102 is moved upward assisted by a spring 105, which has its upper end attached to the framework and 20 has its lower end attached to a pin 106 affixed to a collar or washer 107 mounted on the connecting member 103 and clamped against the lower end of the connecting member 104, by a 25 nut 108 on the threaded end of the connecting member 103.

The pivotal connection of the member 104 with the cam bar 86 and the pivotal or ball and socket connection of the member 103 with the armature 102, enables the link or connecting rod 103, 35 104 to be moved in a substantially straight path without interfering with the rotary movement of the cam ring 52.

The cam bar 86 may also be moved manually 40 by means of a lever 110 pivoted at 112 to the framework of the apparatus and having its inner end forked to extend into slots 114 in ears 115, which are shown in Fig. 1 and are extended from opposite sides of the link member 104.

The apparatus above described is designed 45 among other uses to be employed as an end cell switch in power houses and like stations, where it is desired to add storage battery cells to increase the voltage on the line or to diminish the same as the case may be when the situation arises. 50

The stationary contact members 12 are mounted 55 on a panel or board 120 of insulating material, and each contact member is provided with a stud 121, which is extended through the panel or board 120 and has fastened thereon a terminal 122 for connection with a battery cell (not shown).

The bus bar 14 is also provided with a like stud 124 extended through the panel or board 120 and provided with a socket member 125 for 60 connection with one side of the line or circuit in which the battery cells are to be included or removed therefrom.

The oscillating member or lever 40 is held stationary when the movable contact brushes 16, 17 65 are in their central position with relation to the stationary contact member 12 which is connected with the storage battery cell last added to the circuit. This result is effected by a brake band 126 co-operating with a brake drum 127 on the 70 armature shaft 62 of the motor 60, which brake band is applied to the brake drum 127 by a suitable spring (not shown), and is released by an electromagnet 128 when the latter is energized.

The motor 60 and the brake magnet 128 may 75

be controlled and operated substantially as described in the patent above referred to.

The electromagnets or solenoids 100, 101, which control the movements of the cam ring 52 may be controlled by a suitable switch not shown, and are responsive to the condition of the circuit in which the apparatus is included, so as to energize the solenoids and shift the cam ring forward or backward according to whether a cell 10 is to be added to the working circuit or taken out thereof.

- If a cell is to be added to the circuit so as to increase the strength of the current supplied by the circuit, the solenoid 100 is energized and the cam bar 86 is lifted so as to shift the cam ring 52 in the direction indicated by the arrow 94 in Fig. 6 and thereby cover the right set of teeth 48 on the toothed disk 49 and at the same time uncover the left set of teeth.
- 20 If a cell is to be taken out of the line circuit, the solenoid 101 is energized and the cam bar 86 is lowered so as to shift the cam ring 52 in the direction opposite to that indicated by the arrow 94, and thereby cover the left set of teeth 48 and uncover the right set of teeth, which is the condition represented in Figs. 1 and 6.

At or about the time the cam ring 52 has been shifted as described, the brake magnet 128 is energized to release the brake band, and the circuit of the motor 60 is closed. The motor 60 rotates the toothed disk 49 to the right, Fig. 1, on the forward throw of the connecting rod 73 in the direction of the arrow 74, Figs. 1 and 6, and on such movement, the pawl 47 is lifted by the cams 35 58 and the toothed disk 49 clicks by the pawl 46.

On the reverse throw or movement of the connecting rod 73, indicated by the arrow 130, the toothed disk 49 is rotated in the opposite direction to that indicated by the arrow 74, Figs. 1 and 6, 40 and the pawl 46 drops into engagement with a tooth 48 of the right set, and the disk 49 pushing against the pawl 46 swings the lever 40 toward the left and moves the contact brushes 16, 17 onto the next terminal block.

45 In the present instance five stationary contact members 12 are employed, but it will be understood that a greater or less number of such contact members may be employed and the disk 49 and the cam ring 52 will be provided with teeth 48 and cams 58, 59 to correspond with the change in the number of such stationary contacts 12 used in the apparatus.

Provision is made to open the circuit when the last cell has been added to or taken out of the 55 circuit, and to this end the circuit controllers 132, 133 are affixed to the panel or board 120 at opposite ends of the bus bar 14 and in the path of movement of the oscillating lever 40, so as to be opened by the lever 40 when the latter is 60 moved into its extreme positions to the right and left, with the brushes 16, 17 in the center of either of the end contact members 12.

The movable parts of the apparatus may be 65 protected by a box or casing 140 which is suitably secured to the panel or board 120, and is provided in its front surface with a slot 142 which is curved and has the same center as the oscillating lever 40 and is of sufficient length to display all of the stationary contact members 12 and 70 enable a pointer or index 144 to be seen by the operator.

The pointer or index 144 is secured to the oscillating lever 40 to move therewith.

75 One embodiment of the invention is herein

shown, but it is not desired to limit the invention to the particular embodiment shown.

What is claimed is:

1. In an apparatus of the character described, in combination, an oscillating lever, a shaft on which said lever is mounted, a contact member carried by said lever, a rotatable disk mounted on said shaft and provided with sets of oppositely arranged teeth, a ring loosely mounted on said toothed disk to be rotated thereon and provided with sets of cams co-operating with the sets of teeth on said disk to cover and uncover said sets of teeth, pawls carried by said oscillating lever and co-operating with said toothed disk to effect movement of said lever in opposite directions by rotation of said toothed disk, a cam bar mounted on said toothed disk to move substantially radially thereon and co-operating with said cam ring to rotate said ring on said toothed disk in opposite directions, means for holding said cam bar and said cam ring against accidental movement, and means for oscillating said toothed disk.

2. In an apparatus of the character described, in combination, an oscillating lever, a shaft on which said lever is mounted, a contact member carried by said lever, a rotatable disk mounted on said shaft and provided with sets of oppositely arranged teeth, a ring loosely mounted on said toothed disk to be rotated thereon and provided with sets of cams co-operating with the sets of teeth on said disk to cover and uncover said sets of teeth, pawls carried by said oscillating lever and co-operating with said toothed disk to effect movement of said lever in opposite directions by rotation of said toothed disk, a cam bar mounted on said toothed disk to move substantially radially thereon and co-operating with said cam ring to rotate said ring on said toothed disk in opposite directions, means for holding said cam bar and said cam ring against accidental movement, and means for oscillating said toothed disk.

3. In an apparatus of the character described, in combination, a bus bar, a plurality of stationary contact members arranged in a circle and spaced from said bus bar, contact brushes located on opposite sides of said stationary contact members and said bus bar and having their opposite ends adapted to contact with said bus bar and said contact members, a bolt connecting said brushes and upon which one of said brushes is loosely mounted to slide thereon, an oscillating lever, a hub carried by said lever and through which said bolt is extended to slide therein, said hub having members co-operating with said brushes to move the same bodily in a circular path and between which said brushes are movable in a direction transversely of said circular path, and means for oscillating said lever.

4. In an apparatus of the character described, in combination, an oscillating lever provided with forks, a hub located between and secured to said forks, a bolt loosely extended through said hub, contact brushes mounted on said bolt and individually movable toward and from said hub, and pusher arms for engaging the opposite sides of said brushes to effect bodily movement of said brushes as a unit.

5. In an apparatus of the character described, in combination, a plurality of stationary contact members, a bus bar spaced therefrom, contact brushes co-operating with said bus bar and said

45

50

55

60

65

70

75

stationary contact members on opposite sides thereof, a bolt secured to one of said brushes and upon which the other of said brushes is mounted to move thereon, and means on said bolt for adjusting the pressure of both of said brushes 5 against said bus bar and said contact members.

6. In an apparatus of the character described, in combination, a plurality of stationary contact members, a bus bar spaced therefrom, a bolt extended transversely of said contact members 10 and said bus bar between the same, contact brushes mounted on said bolt on opposite sides of said contact members and said bus bar, one of said contact members being loosely mounted on said bolt to move lengthwise thereof, means 15 on said bolt co-operating with one of said brushes to effect simultaneous movement of said brushes toward each other and into contact with the opposite surfaces of said bus bar and contact members, and a reciprocating carrier through 20 which said bolt is loosely extended.

7. In an apparatus of the character described, in combination, a plurality of stationary contact members, a bus bar spaced therefrom, contact brushes co-operating with said bus bar and said contact members on opposite sides thereof, a 5 supporting member upon which said contact brushes are mounted, one of said contact brushes being loosely mounted on said supporting member to move lengthwise thereof, a reciprocating carrier through which said supporting member 10 is loosely extended to move transversely of the path in which the said carrier is reciprocated, and means on said supporting member co-operating with one of said brushes to move it in one direction toward the path in which said carrier 15 is reciprocated and to simultaneously move the other of said brushes in the opposite direction toward said path, whereby the pressure of the brushes against the bus bar and said contact members at the end of the brushes is equalized. 20

ALF E. ANDERSON.
